UNITED STATES PATENT OFFICE.

ROBERT GRABOWSKY, OF HANOVER, GERMANY.

FURNACE-GRAVE.

1,107,292.

Specification of Letters Patent. Patented Aug. 18, 1914.

Application filed April 22, 1913. Serial No. 762,759.

To all whom it may concern:

Be it known that I, ROBERT GRABOWSKY, a subject of the Emperor of Germany, residing at Hanover, Germany, have invented 5 certain new and useful Improvements in Furnace-Grates, of which the following is a specification.

This invention relates to hollow water cooled grates of a type wherein grate bars 10 are used which are formed with a longitudinal partition wall, the water being caused to flow out along said bars at one side of the partition and to return along the other side thereof.

15 It is the object of this invention to provide an improved type of grate bar for use in such grates; further, to provide an improved water inlet and outlet shell connected to the set of grate bars and supplying the water 20 thereto, and to provide a construction wherein all permanent joints can be made by means of welding whereby the risk of straining and consequent leakage is reduced to a minimum.

25 Other objects will appear from the following description.

In the drawings;—Figure 1 shows a cross section of one form of water chamber, with a grate bar (partly broken away) attached 30 thereto, and also a cross section of the grate bar. Fig. 2 shows a view of part of the water chamber as seen from the left side in Fig. 1, the cover plate being removed. Fig. 3 is a partial sectional view showing 35 a modified form of connection between the water chamber and the grate bars. Figs. 4 and 5 are detail views showing particular forms of grate bars suitable for use according to the invention.

40 Referring first to Figs. 1 and 2, it will be seen that a set of grate bars *c* with longitudinal partitions *i* therein are attached to a water supply shell or box having a lower water inlet compartment *a* and an upper 45 water outlet compartment *a'*, separated by a partition *b*. The box has its top and bottom walls *d'*, *d* and its end walls *e* made from a single strip of weldable or forgeable metal bent to the shape shown, and welded together at its ends. The rear wall *k* is a 50 separate metal plate which is subsequently welded in place after the grate bars *c* have been welded to it, while the front wall *f* forms a removable cover plate which is 55 normally held in place by bolts *g* and nuts.

In fitting the parts together, the grate bars *c* have their open ends inserted in openings in the plate *k* and welded therein, after which the rear edge of the partition *b* is welded to the plate *k* and to the ends of the 60 grate bar partitions *i*. Hereupon the plate *k* is fitted to the back of the box formed by the walls *d*, *d'*, *e*, and its periphery is welded thereon, and then the ends of the partition *b* are welded into the ends *e* of the 65 box.

In the alternative construction shown in Fig. 3, the ends of the grate bars *c* are made to butt against the wall *k* and are welded thereto in that position, while the partition 70 *b* has extensions projecting into the ends of the grate bars and meeting their partitions *i*. The partitions *i* do not extend quite to the outer closed ends of grate bars as seen in Fig. 1, but a space is left for the water to 75 flow up from the lower side to the upper side of the partitions *i* therein.

The bolts *g* are welded to the walls *d*, *d'*, *e*, of the water box, as are also the pipe 80 joint sockets *h* and *h'* by which the water is let into and away from the compartments *a* and *a'* respectively. In this way an extremely strong construction is produced wherein the bars and the water feed box are all in one piece, welded together so as to 85 leave no joints which are at all liable to give rise to leakage or other trouble. The only removable part is the front plate *f* which must be removable for inspection and cleaning purposes, but which is never very 90 much heated in any case nor subjected to serious stresses.

The grate bars are preferably formed as indicated in Fig. 4 or Fig. 5. In either case the bar is made by folding and forming 95 in a rolling operation, from a strip of metal with longitudinal ribs or projections which when brought together form the partition *i*. The top of the bar is at the middle of the strip, and the edges of the strip are 100 brought together and welded to form the bottom of the V-shaped bar. In order to make a substantially watertight joint between the two ribs forming the partition *i*, the one is preferably formed to engage in 105 a recess or groove in the other as shown. The bars may be formed and welded together also in any other convenient manner to produce the desired form thereof.

The grates may be made of any required 110

size or length and with any required number of bars arranged side by side.

Having thus described my invention, what I claim as new and desire to secure by 5 Letters Patent, is:—

A grate bar applicable to grates using liquid cooling, the said bar consisting of a single sheet of material folded over and welded together to form a V-shaped hollow 10 bar, the sheet having projections thereon

which co-act in the finished bar to form a longitudinal partition therein.

In testimony whereof I have hereunto set my hand in presence of two subscribing witnesses.

ROBERT GRABOWSKY.
